(57) **CLAIM**

What is claimed is the ornamental design for a backup alarm, as shown and described.

DESCRIPTION

FIG. 1 is a front elevational view of a backup alarm;
FIG. 2 is a left side elevational view of the backup alarm;
FIG. 3 is a right side elevational view of the backup alarm;
FIG. 4 is a front right perspective view of the backup alarm;
FIG. 5 is a front left perspective view of the backup alarm;
FIG. 6 is a rear elevational view of the backup alarm;
FIG. 7 is a rear right perspective view of the backup alarm;
FIG. 8 is a rear left perspective view of the backup alarm;
FIG. 9 is a top plan view of the backup alarm;
FIG. 10 is a front top perspective view of the backup alarm;
and,
FIG. 11 is a rear top perspective view of the backup alarm.
A bottom view of the backup alarm forms no part of the claimed design.
